UNITED STATES PATENT OFFICE.

JOHN H. NELSON, OF CHICAGO, ILLINOIS, ASSIGNOR TO CASKEY-DUPREE MANUFACTURING COMPANY, OF COLDWATER, MICHIGAN, A CORPORATION OF OHIO.

ELECTRIC SWITCH.

Application filed June 3, 1925. Serial No. 34,550.

My invention relates to electrical switches and is of particular service in conjunction with ignition switches employed upon automotive vehicles, being of especial utility 5 when embodied in a combined ignition and lighting switch.

In carrying out my invention I employ a handle in lost motion connection with a circuit closing member for the ignition circuit, 10 the amount of the lost motion to be taken up before this member is closed by the handle being known by those authorized, and being only ascertainable by others upon experimentation which would cause such delay 15 in making the ignition circuit operative as would discourage an automobile thief. Ignition switch locks may thus be dispensed with.

Where my invention is embodied in a combined ignition and lighting switch, I employ 20 a lighting switch member operable by the same switch handle and which is in controlling relation to the main head light circuits and the tail light circuit while the ignition circuit closing member is closed and 25 during the portion of the range of the movement of the handle when the handle is out of operating relation with this ignition switch member. The parking light circuits and the tail light circuit, also, may be closed 30 by the lighting switch member when the ignition circuit is open.

The invention will be more fully explained in connection with the accompanying drawings in which Fig. 1 is a rear or bottom view 35 of the switching mechanism of my invention as it is preferably constructed; Fig. 2 is a sectional view on line 2-2 of Fig. 1; Fig. 3 is a sectional view on line 3-3 of Fig. 2; Fig. 4 is a sectional view on line 4-4 of 40 Fig. 2; Fig. 5 is a sectional view on line 5-5 of Fig. 3; Fig. 6 is a front view on a reduced scale; and Fig. 7 is a diagram showing one arrangement of circuits and the switching mechanism of my invention as it 45 is preferably related thereto.

The circuit controlling handle 1 has a hub portion 2 formed with wings or flanges 3 at its circular base or inner end 4. This circular hub base is freely received within a 50 circular opening 5 formed through and coaxial with the mounting and escutcheon plate 6 that has openings 7 by which it and the switch assembled therewith may be mounted upon an automobile dash board or 55 other support. The cylindrical switch cas-

ing 8 is assembled coaxially with and behind the plate 6 by means of rivets 9, the outer or front end wall 10 of the casing being depressed to afford a narrow space in which the wings or flanges 3 of the handle may 60 freely move when the handle is turned upon the axis defined by the circular edge of the opening 5. A rotatable contact actuator 11, preferably a ring of insulating material, is 65 assembled with the inwardly extending continuations 12 of the hub 2 that enter recesses 11' in ring 11, this actuator being located within the casing between the outer end wall 10 of the casing and the insulating contact carrying disc 13 which closes the inner end 70 of the casing. A rotatable contact carrier 14, shown in the form of a metallic ring, is interposed between the elements 11 and 13. The ring carries contact buttons 16, 17, 18, 19, engageable with certain of the contacts 75 20, 21, 22, 23, 24, 25, 26, 26', 27, which are provided upon the contact carrier 13 and are positioned to be engageable at the inner face of this carrier. The buttons 16, 17, 18, 19 have spring barrel extensions upon the other 80 side of the carrier 14, these spring barrels housing springs 29 which press plungers 30 into recesses formed in the ring 11. The handle, when turned, will turn the ring 11 and the ring will turn the contact carrier 85 14 through the intermedium of the plungers 30. Another rotatable contact actuator 31, pertaining to the auxiliary switch, is interposed between the casing wall 10 and another rotatable contact carrier 32 90 which is in the form of a triangular metallic plate. This latter contact carrier has contact buttons 33, 34 thereon which are respectively engageable with the battery and ignition circuit contacts 35, 36 upon carrier 95 13, contacts 33, 35 being upon one side of the common axis of the contact carriers and actuators. A non-electrical button 33' moves upon the insulation 13 to keep carrier 32 level. The contacts upon this carrier pertain to the ignition and main head light circuits, contact 25 upon the carrier 13 pertaining to the ignition circuit alone.

Two symmetrically related series of marks each containing marks *a*, *b*, *c*, *d*, *e*, *f*, *g*, and *h* 105 are arranged equal distances on opposite sides of the "off" position of the handle 1, Fig. 7, these marks being arranged upon the escutcheon plate 6. All of the switches being produced by the manufacturer have all 110

of these marks on their escutcheons, the different switches having other lugs 11², 31', of various sizes so that in one switch the electrically connected contacts 33 and 34 are brought in connection with the contacts 35 and 36 when the switch handle index 1' is brought to a mark *h*. In another switch said lugs would be of such size that this result would be effected when the handle index 1' is at a mark *g*; etc. In the switch illustrated the contacts 33 and 34 are engaged with the contacts 35 and 36 when the handle index 1' is brought to a mark *f*. To insure this result the handle 1 is turned from whatever position it may happen to occupy a complete revolution and enough more to bring it to the proper mark, in this instance either of the marks *f*, depending upon the direction of the revolution of the handle. The other marks that are not employed in the particular switch with which the user is supplied, serve to confuse anyone tampering with the switch. When the switch contacts 33 and 34 have been thus adjusted into connection with the battery contacts 35 and 36, the handle is reversed in position to bring the handle index 1' from the region of the arcuate rows of marks *a* to *h* inclusive, into the region of the arcuate row of marks that are designated "Park", "Day", "Off", "Dim", and "Brit". The switch handle may be turned to bring its index 1' into register with any of the latter marks to respectively close the park lighting circuits, the bright headlight circuits, the dim headlight circuits, (and also the tail light circuit with either of the aforesaid three circuits) or into register with the "Day" mark in which none of the lighting circuits is closed while the ignition circuit remains closed, or into register with the "Off" mark in which all lighting circuits and the ignition circuit are opened, all as will more fully hereinafter appear. That is, the arrangement is such that there is lost motion between the lug 11² which always moves with the handle and the lug 31' when the contact actuator 31 having this lug is positioned to connect the contacts 33 and 34 with the contacts 35 and 36, this lost motion of the lug 11² with respect to the lug 31' occurring in the arcuate section of the travel of the handle index 1' that is above both marks *f* in the particular switch illustrated. The control of the various lighting circuits and the control of the ignition circuit that supplements the control of the ignition circuit effected by the contact actuator 31, occurs when the handle is being so moved as to cause the handle index 1' to move in the segment of the circular path of travel of this index 1' that is above the segment which terminates at points corresponding to the marks *f*. The device of my invention, therefore, does not interfere with the normal operation of a combined ignition

and lighting switch but adds to such a switch structural features whereby the ignition circuit may be opened at a second place and rendering guess work necessary on the part of a tamperer to close it at this second place an arrangement which makes it unnecessary to employ a key controlled lock. There is always lost motion possible between the lugs 11² and 31' whether the contacts 33 and 34 are in connection with the contacts 35 and 36 or not, and if the contacts 33 and 34 are in connection with the contacts 35 and 36, the switch structure is such that the parking lights may then alone be displayed, as will hereinafter appear. 80

Obviously, the cooperating positions of the lugs 11² and 31' do not need to underlie the two sets of marks *a* to *h*, but may be anywhere in the circle of rotation of said lugs. As illustrated, the contact actuator 31 is rotatably supported upon the handle by means of a pivot pin 37 that enters the socket 38 in the contact actuator 31 and is carried by the wall 39 at the inner end of the handle hub, the pivot pin 37 and the circular contact carrier 31 being coaxial with the handle hub. 85

The preferred circuit arrangement is diagrammatically illustrated in Fig. 7. The internal combustion hydro-carbon engine 45 is in driving relation to the automobile or other automotive vehicle and also the generator 46 that is in charging relation to the storage battery 47, the generator also supplementing the battery as a source of current, all as is well known. The engine also operates an interrupter 48 which is included in an inducing ignition circuit arranged to be supplied with current from the battery or generator and which includes the primary or inducing winding 49 having one terminal 100 connected with the arcuate contact 25 and its other terminal grounded through the interrupter and also through the condenser 50 that are in shunt relation. The engine also operates the timing switch 51 whose switch arm is in the induced ignition circuit that contains the induced winding 52, as is understood. The main head lamps 53 and 54 are in parallel, being connected by the common conductor 55, with the contact 26' and with contact 26 through the light dimming resistance 28. The front parking or supplemental head lamps 56 are in parallel, being connected by a common conductor 57 with the contact 22. The usual tail light 58, also available as a rear parking lamp, is connected with the contacts 20 and 24. The battery and generator are permanently connected with the contacts 27 and 36. The battery and generator are placed into and out of connection with the arcuate contacts 21 and 23 by suitable adjustment of the contact carrier 32 effected as hitherto described, the contacts 33, 34 closing a common gap in the inducing ignition circuit and the main head 110

115

120

125

130

lamp circuit when these contacts engage contacts 35, 36, the remaining gap in the ignition circuit being closed when the arcuate ignition contact 25 is in circuit with one or the other of the arcuate contacts 21, 23. The remaining gap in the main head lamp circuit is then also closed by the engagement of the contact 19 with either contact 26 or 26'. Thus, the ignition and main head lamp circuits include the contacts 34, 36, while the parking circuits are always adapted to be opened and closed independently of these contacts. By this arrangement, the main head lamps can not glare when the ignition is open and the car is parked. When the switch is in "Off" position, all circuits controlled thereby are open. In the "Off" position, the contact 17 upon the metallic contact carrying ring 14 engages the contact 22 but as the ring is not then connected with either of the current source contacts 21 or 23, the front parking lamp circuit is not continued beyond contact 17 and ring 14, this parking lamp circuit thus being then open. The contacts 19 and 25 are also then in engagement but the ignition circuit is then properly open at 33, 34, 35, 36, as well as being open by the disconnection of the ring from contact 21 or 23. The tail lamp circuit is then open for a similar reason, as is also the main head light circuit.

When the switch is placed in "Day" position, contact 17 engages the battery contact 21 and contact 19 remains in engagement with the ignition circuit contact 25, making the ignition circuit effective and controllable by the handle if it is closed at its gap 33, 34, 35, 36. When the switch is in its "Day" position, none of the lighting system contacts is in circuit, the ring 14 having then no connection therewith.

When the switch is in "Park" position, contact 19 is disengaged from contact 25 to break the ignition circuit at this point, the switch then also being thrown to open circuit at 33, 34, 35, 36. Contact 17 then engages contact 20; contact 19; contact 24; contact 18; contact 22; and contact 16; current source contact 27 to close circuit through the front parking lamp 56 and the tail or rear parking lamp 58. If the switch is in "Dim" position, contact 17 engages contact 23 and contact 19, contact 26, to establish circuit for the main head lamps 53, 54 through resistance 28 to furnish dim light at the main head lamps providing contact 34 engages contact 36. The contact 18 then engages the ignition circuit contact 25 to close the ignition circuit gap at this point, this circuit as well as the main head lamp circuit being finally closed or open at 33, 34, 35, 36. The tail or rear parking lamp 58 is then also connected in circuit by the engagement of the contacts 16 and 20. The front parking lamps are then in open cir-

cuit as their contact 22 is not then in connection with ring 14. If the switch is thrown to "Bright" position, contact 19 engages contact 26' and contact 16 engages current source contact 21 to close circuit 70 through the main head lamps 53, 54 exclusively of the dimming resistance 28. At this time contact 18 still engages ignition contact 25 to render the ignition system operative if the contacts 33, 34, 35, 36 are in 75 connection. The tail lamp circuit is then also closed because of the engagement of contacts 17 and 24, but the front parking lamps are then not in circuit because their contact 22 has no connection with the ring 80 14. The gaps between contact 22 and contacts 21 and 23 are narrower than the ring contacts engaging them, and the gaps between contact 24 and the contacts 23, 25 are narrower than the ring contacts engaging 85 them to keep the main head lamp circuit intact while changing between "Dim" and "Bright" and to prevent the ignition circuit from being opened whatever may be the adjustment that is being effected of the light- 90 95 arrangement by the switch.

In some systems the front parking illumination is effected by a dimming of the head lamps and without employing supplemental head lamps. I do not, therefore, 95 wish to be limited to the employment of supplemental head lamps in the front parking light circuit, nor do I wish to be limited to the character or purpose of the light circuits which, with or apart from the ignition circuits are governed by the switch 100 handle.

Changes may be made without departing from my invention.

Having thus described my invention, I 105 claim:

1. An electric circuit controlling switch constructed to prevent its unauthorized circuit making and breaking manipulation comprising a casing, a pair of rotatable contact carriers within said casing, one of which is in the form of a ring and the other of which is located within the one of ring form, a lug projecting inwardly from said first mentioned contact carrier and a lug projecting 110 outwardly from said second mentioned contact carrier, said lugs cooperating to produce a lost motion connection between said contact carriers, and an operating handle outside said casing connected with one of said 115 contact carriers.

2. An electric circuit controlling switch constructed to prevent its unauthorized circuit making and breaking manipulation comprising a casing, a fixed contact carrier 125 within said casing, a pair of movable contact carriers within said casing having contacts, respectively, adapted for cooperation with contacts carried by said fixed contact carrier, one of said movable contact carriers 130

being in the form of a ring and the other being located within the one of ring form, a handle movably mounted on said casing and extending exteriorly of the latter, said handle being connected with said contact carrier of ring form for moving the same, a pin extending from a portion of said

handle within the casing, said second mentioned movable contact carrier being mounted on said pin, and a lost motion connection 10 between said movable contact carriers.

In witness whereof, I hereunto subscribe my name.

JOHN H. NELSON.
